UNITED STATES PATENT OFFICE

FRANK E. ERICKSON, OF MELROSE, MASSACHUSETTS

COLLAPSIBLE FIREPLACE

Application filed May 31, 1930. Serial No. 458,603.

The object of this invention is to provide a collapsible fireplace which can be set up against a flat wall or in the corner of a room to simulate a real fireplace and the parts of which can be placed together so that they will occupy but little space when not in use.

This invention also consists in certain other features of construction and in the combination and arrangement of the several parts 10 to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a view showing the fireplace set up.

Figure 2 is a view showing some of the parts arranged in another part so that the parts will occupy but little space when not in use.

Figure 3 is a view of the blank from which the body of the device is formed.

Figure 4 is a view of the blank from which the shelf is formed.

Figure 5 is a view of the blank from which the chimney is formed.

Figure 6 is a section on line 6—6 of Figure 1.

Figure 7 is a view showing the device set up in the corner of a room.

Figure 8 is a view similar to Figure 7, but showing a slightly different arrangement of the chimney forming part.

Figure 9 is a perspective view of the shelf when used, as shown in Figures 7 and 8.

Figure 10 is a rear perspective view of the body when used with the shelf arranged as shown in Figure 9.

Figure 11 is a rear perspective view of the chimney forming part as used in the first form of the invention.

Figure 12 is a vertical sectional view through the upper part of the body and showing the shelf thereon.

The body 1 is formed of a sheet or blank A which is folded on the lines α so as to form the front 5, the back 6 and the two sides 7. The

blank is also folded on the horizontal lines α' to form the flaps 8, 9, 15 and 16, these flaps being cut, as at 10, the cuts being in alignment with the fold lines between the sides and the front and back parts. The flaps 8 and 9, at the front, are folded so that the flap 8 is folded outwardly and the flap 9 inwardly, so that they will extend at right-angles to the front. Flaps 15 and 16, at the back, are folded inwardly and then the parts 11 between the cuts 10 are folded upon the flaps 9, 15 and 16, as shown in Figure 6. Thus when the blank is folded as described, a rectangular body will be formed, as shown in Figure 1. The front is cut on the lines β so as to provide two flaps 12 which are folded inwardly to form the side walls of the fireplace opening 13, the free edges of these flaps engaging the back 6 and the bottom flap 15 which forms the floor of this opening. The front flap 8 forms the hearth. In Figure 6, the full lines show the fireplace as placed against a flat wall of a room. If the fireplace is to be used in a corner of the room, as shown in Figures 7 and 8, the triangular tongues 14, cut on the lines γ in the back 6, will be bent outwardly so as to support the flap 17 of the shelf, as shown in dotted lines in Figure 6.

The shelf 3 is formed of a blank B which is of the shape shown in Figure 4, and this blank is folded on the lines δ so as to form a shelf of a certain thickness, as shown in Figure 1. This shelf is placed on the top of the body, with its front and rear parts extending over the top part of the body, as shown in Figure 6.

This shelf is formed with the rear flap 17 which is bent downwardly when used with the arrangement shown in Figure 1, as shown in full lines in Figure 6, but when the device is used in a corner, as shown in Figures 7 and 8, the shelf is bent into horizontal position and rests on the tongues 14, as shown in dotted lines in Figure 6.

The chimney 4 is formed of a triangular shaped blank C folded on the lines ϵ to provide a chimney shaped as shown in Figure 1, with a flat straight back and sides and a sloping front.

The upper flap *c* of the chimney is bent downwardly as shown in Figure 11, when the device is used as shown in Figure 1, but when used in the corner of a room, this flap and the side flaps can be bent at an angle, as shown in Figure 8, or the side and top flaps can be left straight, as shown in Figure 7, with the edges resting against the walls as shown in said figure.

- 10 Thus when the parts are to be assembled, the body 1 is placed in position on the floor. The shelf is then placed on the body and finally the chimney is placed on the shelf. This produces a fireplace which may be used
- 15 at Christmas to simulate a real fireplace and when the device is not to be used, the chimney and shelf are placed in the body, as shown in Figure 2, so that the device will occupy but little space when not in use.
- 20 It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

- 25 A fireplace of the character described comprising a blank of sheet material cut and folded to provide a unitary body having sides, back and an open front to present an open fireplace, said blank being further cut and bent to form flaps constituting sides of the fireplace and also a bottom therefor, extensions cut and bent from the back, a shelf section forming a top for the body and having its rear portion resting upon the extension, a false chimney superimposed upon the shelf, and a marginal edging at the front and end of the shelf and bent downwardly and inwardly to confront the front and sides.

In testimony whereof I affix my signature.

FRANK E. ERICKSON.
